UNITED STATES PATENT OFFICE.

HARRISON HOUGH, OF DARLINGTON, WISCONSIN, ASSIGNOR TO HIMSELF
AND LEWIS T. LILLIE, OF SAME PLACE.

NECK-YOKE ATTACHMENT.

SPECIFICATION forming part of Letters Patent No. 250,919, dated December 13, 1881.

Application filed October 6, 1881. (No model.)

To all whom it may concern:

Be it known that I, HARRISON HOUGH, of Darlington, in the county of Lafayette and State of Wisconsin, have invented a new and useful Improvement in Neck - Yoke Attachments; and I do hereby declare that the following is a full, clear, and exact description of the same, reference being had to the accompanying drawings, forming part of this specification, in which—

Figure 1 is a side elevation of my improved neck-yoke attachment. Fig. 2 is a bottom-plan view of same.

My invention relates to improvements in devices for preventing a wagon-tongue from accidentally becoming detached from the neck-yoke and dropping to the ground; and it consists in the peculiar construction and arrangement of the parts, as hereinafter more fully set forth.

In the accompanying drawings, *a* represents a wagon-tongue provided with the holdback *b*, both of the usual construction.

c represents a spring safety-hook, the inner end of which is secured to the under face of the tongue, preferably by screws. The spring-hook *c* is provided with a slot, *d*, through which the holdback passes, the tension of the spring-hook causing its hook *e* to bear against the tongue *a* near its outer end.

h represents the ring of the neck-yoke, of the ordinary construction.

k represents a ring inserted in the loop of the ordinary holdback, to act as a stop for the spring safety-hook *c*, or prevent the safety-hook from springing down too low in case it should accidentally be caught and forced down.

In practice the ring of the neck-yoke is slipped on the tongue in the usual manner, when it will spring back or force down the safety-hook and pass behind it, and if the neck-yoke is pulled forward it wedges the hook tighter against the tongue, and the hook must be sprung back by hand in order to remove the ring of the neck-yoke.

By this construction it will be seen that all liability of the neck-yoke becoming detached from the tongue is obviated, the ring of the neck-yoke being prevented from slipping off the outer end of the tongue by the hook, and prevented from slipping backward by the holdback, and that the spring safety-hook can readily be applied to a tongue with the ordinary holdback, *b*, in common use, by simply attaching my safety-hook to the under face of the tongue with screws and placing a ring in the loop of the holdback, thus rendering the construction extremely simple, cheap, and effective in preventing the dropping of the tongue, and adapting its employment to ordinary wagon-tongues.

I claim as my invention—

The combination, with a wagon-tongue provided with a neck-yoke ring, *h*, and holdback *b*, having ring *k*, of the spring-hook *c*, secured at its inner end to the under face of the tongue, and provided with a slot, *d*, for the passage of the holdback, substantially as described, and for the purpose set forth.

HARRISON HOUGH.
